MECHANICAL COUNTING RELAY

Kenneth W. Graybill, Elmhurst, and Hans Sengebusch, Villa Park, Ill., assignors to Automatic Electric Laboratories, Inc., Chicago, Ill., a corporation of Delaware

Application December 1, 1949, Serial No. 130,454

10 Claims. (Cl. 177—353)

1

This invention relates in general to selector switches of the type employed in the automatic telephony art and more particularly, to the counting relay type thereof.

Accordingly, an object of the invention is to provide an improved counting relay type stepping switch.

A feature of the invention lies in the individual latching mechanisms corresponding to digit impulses to be counted.

Another feature of the invention is its adaptation to a continuous chain like operating sequence.

A further feature in keeping with the last mentioned feature is a bail and pin arrangement insuring said continuous chain like operating sequence.

These and other objects and features will be more particularly pointed out in the ensuing specification taken in conjunction with the accompanying drawings in which Fig. 1 is a perspective view from the left and front of the device.

Fig. 2 is an isometric view of one of the driving members and shows its interconnection with a group of four contactors.

Fig. 3 is an isometric view of one of the cocking elements of the device.

Fig. 4 is a side section of the first and second driving members, their associated cocking elements and springs as well as the bail and pin.

Fig. 5 is a side section showing the same elements as Fig. 4 except that the first driving member and associated cocking mechanism is in its forward or operated position.

Fig. 6 is a side section showing the same elements as Fig. 4 with the first driving member returned to normal and the second one lowered into its operate position.

Fig. 7 is an oblique view of the first three driving members, associated cocking elements, bail and pin and common driving armature.

Referring now to the drawings, a detailed description of the mechanism and its operation follows.

Here also, as stated in our co-pending application, Serial No. 115,468, filed September 13, 1949, to which reference may be had, the instant invention presents a rather complicated mechanism, and to facilitate the description and render it more readily understandable, locative or directional adjectives such as rear, forward and so forth will be used. For this purpose, the reference positions used will be the left and front sides of the device as shown in the perspective view in Fig. 1.

2

The device is mounted on a frame 1 which may be a cold rolled steel stamping. Frame 1 has a base portion 2 at the rear of which and rising perpendicularly therefrom is heelpiece 3. Two driving magnets 6 and 7 are mounted side by side on the lower portion of heelpiece 3 just above the base portion 2. Above the magnets 6 and 7 rigidly connected to and extending perpendicularly forward from the lateral edges of heelpiece 3 are ears 4 and 5. Secured to the outer surfaces of ears 4 and 5 and extending in parallel relationship rearward are ears 8 and 9. These ears 8 and 9 are made of an electrically non-conducting material. Along the upper edges of ears 8 and 9 and rearward of heelpiece 3 are bored four spaced apart holes into which are set four bar contacts 10. These bar contacts 10 all lie in a plane parallel to base 2 and each bar 10 parallels heelpiece 3 as well. The left ends of bar contacts 10 project beyond the outer surface of ear 8 and terminate in flattened end contacts 11. Below and to one side of three of the bar contacts 10 are bored into ears 8 and 9 three more spaced apart holes and passed therethru are three insulated bar rests 12. Bar rests 12 also lie in a plane paralleling base 2 and each parallels the heelpiece 3 and the bar contacts 10 while being positioned below and slightly rearward of the first three of bar contacts 10 counting front to rear. Beneath base portion 2 and attached to the lateral sides thereof is a sub-base element 13 which extends rearward beneath heelpiece 3, then rising in a vertical wall 14 flush against the rear of heelpiece 3 and extending laterally therebeyond. Attached to vertical wall 14 by means of a clamping plate 15 and bolts, not shown, are twelve ranks of contactors 16, each rank comprising four contactors 16 one behind the next, separated one from another, and held in place by insulating strips 17 near the lower ends thereof between clamping plate 15 and vertical wall 14. The upper ends of these contactors 16 extend upward a proper distance to permit engagement with bar contacts 10. Eleven of these ranks of four contactors each are positioned between ears 8 and 9 while one rank is positioned outwardly adjacent ear 8 and extends to contact the flat ends 11 of the bar contacts 10 which were stated to extend beyond ear 8. The twelve ranks of contactors 16 form four files, each file positioned forwardly of its associated bar contact 10. Each of the three rearwardmost contactors 16 in each rank of the eleven ranks between ears 8 and 9 is tensioned so as to bear against the insulating bar 12 in front thereof; while the front contactors 16 in each of the

eleven ranks are tensioned to bear against the frontmost studs 24 on the associated driving members 20 subsequently described. All eleven ranks of contactors 16 within the confines of ears 8 and 5 are movable into engagement with the bar contacts 10, one rank at a time, the mechanism for which will be described hereinafter, while the twelfth rank of contactors 16 outside of ear 8 is tensioned so as to be in contact with bar contact ends 11 at all times. Each of the contactors 16 terminates at its other end in a terminal 16a. Each of the contactors 16 may at its upper contacting end be split to form twin contacts as shown in Figs. 1 and 2 thereby doubly assuring good contact with bars 10.

Ears 4 and 5 have axially holes bored there-thru serving as bearing surfaces for shaft 18. On shaft 18, between ears 4 and 5, equally spaced apart are ten cocking elements 19 (Fig. 3). Situated above these ten cocking elements 19 are eleven driving members 20 and disposed longitudinally thru the switch, front to rear, are eleven driving members 20 (Fig. 2). All eleven driving members 20 are movably mounted so as to have a range of operation both longitudinally in and out as well as a pivoted vertical movement up and down. To maintain the driving members 20 in proper lateral spaced-apart relation and from lateral displacement, a flat cross piece 21 is placed across the bar of the switch supported at either end by ears 8 and 9. Cross piece 21 has eleven spaced-apart vertical slots to receive the rear-most ends of the driving members 20, the lower edges of the members 20 resting on the lower edges of the associated slots. Each driving member 20 at its rearmost end has a small recess 22 along its upper edge terminating in a raised hook 23 at its very end. Recesses 22 and hooks 23 limit the length of the longitudinal movements of the driving members 20, the forward edge of recess 22 engaging the upper edge of its associated slot in cross piece 21 to stop its front-to-rear stroke while the hook end 23 engages the upper edge of its associated slot to limit the return stroke thereby. Also, the recessed rear ends of the driving members 20 within their associated slots in cross piece 21 furnish a pivotal point on which the driving members 20 can be raised or lowered vertically from their forward ends by means to be described hereinafter. Forward of recesses 22 and on the left hand side of each driving member 20 project five insulated studs 24. These studs 24 engage an associated rank of four contactors 16 (Fig. 2) so that when a driving member 20 is moved longitudinally rearward the associated rank of contactors 16 is pushed into contact with the bar contacts 10. Further forward each driving member 20 is held from lateral displacement by being placed between teeth in a comb-like cross member 25 which is attached as by bolts to heelpiece 3 (Fig. 4) and extends its comb-like teeth thereabove for the purpose stated. Immediately below each driving member 20, except the first driving member 20 adjacent ear 8, is positioned an associate cocking element 19 (Fig. 3). Each cocking element 19 has a vertical finger 26 in one plane and a curved finger 27 and a lower hook 28 in an adjacent parallel plane, all three parts rigidly connected together by panel 32. All cocking elements 19 are rotatably mounted on shaft 18, curved fingers 27 thereof positioned between the teeth of the comb-like member 25 below their individually associated driving members 20. The vertical

fingers 26 are positioned to engage at normal a stud 29 projecting from each driving member 20 immediately to its left. To maintain each vertical finger 26 in engagement with a stud 29 projecting rearwardly to the right from the associated driving member 20 immediately to its left, small springs 31 (Fig. 4) are attached to lower hooks 28 of cocking elements 19 at one end and at their other ends to hooks 32 secured to heelpiece 3 therebehind. The force of these springs 31 will at normal tend to rotate the cocking elements 19 clockwise (Fig. 4) and so hold fingers 26 in engagement with studs 29 of driving members 20 to the left thereadjacent as well as holding the associated driving member 20 thereabove in its upper normal position by means of finger 27.

Along its lower edge, each driving member 20 is provided with a cocking step 33. At normal, each driving member 20 rests in this step 33 upon the tip of hooked finger 27 of its associated cocking element 19 therebelow. To forwardly hold and return the driving members 20 to this position which is the normal position, small springs 34 (Figs. 4, 5, 6) are connected at one end to arms 35 rigidly connected to and extending centrally above each driving member 20 and at the other end to hooks 36 on a forward cross member 37 which lies above all driving members 20 near their forward ends and is connected to ears 4 and 5 for support (Fig. 1). The force of these springs 34 tends to keep the driving members 20 at normal forward against their rearmost hook stops 23 described hereinbefore.

Another shaft 48 is mounted between ears 8 and 9 in axially aligned holes therein. Shaft 48 is above but rearward of cocking element mounting shaft 18 and is positioned below all driving members 20 and just behind all vertical fingers 26 of cocking elements 19. To this shaft 48 is forwardly attached a U-shaped bail 38 (Fig. 7) which extends under all driving members 20 except the first one adjacent ear 8. Rearward of shaft 48 and attached thereto near its left end is an L-shaped pin 39 which extends its short leg just under the first driving member 20 adjacent ear 8. This bail and pin arrangement is for accommodating the lowering of the first driving member 20, the member on the left-hand side of the switch (Fig. 1), into its operate position after the last driving member 20, the right-hand member 20 of the device (Fig. 1), has been operated and returned to normal as will be explained in detail hereinafter when the overall operation of the device is described.

Also pivotally mounted on a third shaft 40 (Fig. 4) supported in axially aligned holes in ears 4 and 5 is an armature 41. Armature 41 is so constructed as to be common to all eleven driving members 20. It normally rests just below the forward ends of all the driving members 20 except a particular one driving member 20 which has been lowered into its operate position. Because of its operating path, armature 41 can then engage only such driving members 20 as are lowered into their operate position. The armature 41 is attracted at its lower end to magnets 6 and 7 when they are energized. It will be obvious that one centrally disposed magnet should suffice in lieu of two, if desired. Upon de-energization of magnets 6 and 7, the upper edge of armature 41 is pulled toward the lowered driving member 20 by a strong retractile spring 42 (Figs. 1 and 4) connected at one end to a hook 43 attached to heelpiece 3 (Fig. 4) and at the other end to a

hole 44 provided therefor in armature 41. Even though the instant embodiment is indirectly magnet driven, by slight re-arrangement as by lowering shaft 40 and spring 42 to a position below the magnets, the device could as easily be directly driven instead of indirectly driven by force of retractile spring 42. Spring 42 pulls armature 41 against any lowered driving member 20 in its operating path and pushes it rearward, the complete operation to be explained more fully hereinafter.

Finally, armature 41 is provided with a left side arm 45 and buffer 46 at the end thereof to engage and open a set of interrupter springs 47 attached to base 2 each time the magnets are energized pulling the upper edge and attached arm 45 of the armature 41 away from the driving members 20. The magnets 6 and 7 operating circuit may be connected to these interrupter springs 47 to effect a stepping operation in well known manner and will not be further detailed, or also, in well known manner, the magnets 6 and 7 may be energized by a pulsing into them as by dial interruptions effecting a stepping independent of the interrupter springs 47.

Having described the mechanism of the device, the operation is as follows:

Assuming all the driving members 20 to be at normal, and also assuming that the first impulse is received by the magnets 6 and 7 causing the magnets 6 and 7 to attract the armature 41 into its forwardmost position, the first driving member 20 adjacent ear 8 will be lowered at its frontmost end to its operate position by the force of its associated spring 34 as there is nothing to hold it up out of the operating path of armature 41. Also bail 38 is in its uppermost position under the remaining ten driving members 20 which are in their upper normal positions, and L pin 39 is therefore in its lower position under the weight of the first driving member 20. This is best visualized by looking at Fig. 7 where it becomes rather obvious that L pin 39 and bail 38 act in a "see-saw" fashion; when one is up, the other must be down. If the pulse into the magnets 6 and 7 is thru interrupter springs 47, buffer 46 will open the interrupter contacts and the magnets 6 and 7 will de-energize thereby or, if directly pulsed, the magnets 6 and 7 will de-energize after the duration of the pulse. Then, retractile spring 42 pulls the armature 41 in toward the switch where it drives the first driving member 20 rearward until halted at its full rearward stroke by the forward edge of recess 22 thereon, coming in contact with the upper edge of the slot in cross piece 21. In moving rearward, stud 29 of the first driving member 20 adjacent to ear 8 engages vertical finger 26 of the cocking element 19 associated with the next or second driving member 20 and rotates it on shaft 18 counter-clockwise (Fig. 5). In so doing, curved finger 27 of the cocking element 19 is likewise rotated downward releasing its support from under the second driving member 20, whereby the second driving member 20 moves slightly forwardly under the bias of the associated spring 34 moving the cocking step 33 forwardly with respect to its normal position directly above the end of the curved finger 27. At this time, except for the position of the armature 41 immediately beneath the forward end of the second driving member 20, the forward end thereof would drop. Meanwhile, the first group of contactors 16 inwardly adjacent ear 8 and engaged by insulated studs 24 on the first driving member 20 are

pushed from against rests 12 into contact with the four bar contacts 10 simultaneously. The first group of contactors 16 are thus held closed until the magnets 6 and 7 are again energized.

Upon the next energization of the magnets 6 and 7, as the armature 41 is attracted thereto and away from the driving members 20, the second driving member 20 is free to drop at its forward end under the force of its associated spring 34 and does so. In dropping, the second driving member 20 depresses bail 38 causing L pin 39 to rise, the latter lifting the first driving member 20 up out of the operating path of the armature 41, the spring 34 associated with the second driving member 20 being somewhat stronger than the spring 34 associated with the first driving member 20. Coil spring 34 causes the first driving member 20 to return forward as the armature 41 is being attracted to the magnets 6 and 7, releasing the engaged rank of contactors 16 from bar contacts 10 and returning them against insulated bar rests 12.

The magnets 6 and 7 upon de-energizing again permit retractile spring 42 to pull the armature 41 in toward the driving members 20 where it now engages only the second, lowered driving member 20 and drives it rearward to its full stroke in the same manner as described for the first driving member 20. This movement in turn causes the stud 29 on the second driving member 20 to engage the vertical finger 26 of the cocking element 19 associated with the third driving member 20 and rotates it counter-clockwise disengaging its connected curved finger 27 from cocking step 33 on the third driving member 20 preparing it to drop when the armature 41 is again attracted away from its forward underportion. Also the second rank of contactors 16 is pressed into contact with bar contacts 10. Upon the next energization of the magnets 6 and 7, as with the second driving member 20, the third driving member 20 falls keeping the bail 38 down which of course keeps the first driving member 20 up due to L pin 39. The second driving member 20 is then likewise urged forward by its spring 34, but unlike the first driving member 20, is now also urged upward to its normal position by spring 31 rotating the associated cocking element 19 clockwise causing curved finger 27 to push the driving member 20 upward until with its forward return stroke, it locks in step 33.

This sequence is now continued as long as the magnets 6 and 7 are pulsed. Should a train of less than ten pulses be sent into the magnets, then a subsequent set of pulses will begin with the next adjacent dropped driving member 20. When the eleventh and last driving member 20 which has no stud 29 since there is no adjacent cocking element 19 to engage, has been dropped and driven, whether by a single train of pulses or by a series of lesser trains of pulses, upon restoring, its individual cocking element spring 31 urges it upward into normal position. Bail 38 then rises as L pin 39 is lowered due to the first driving member 20 being lowered to its operate position by the force of its associated spring 34. The switch will thus function in continuous chain fashion as long and as often as its magnets 6 and 7 are pulsed.

Having described our invention in detail, what we claim and desire to be protected by issuance of Letters Patent of the United States is:

1. In a counting device including a magnet for receiving a series of magnetizing impulses, a plurality of movably mounted driving members

respectively corresponding to the impulses of said series, an armature operatively associated with said magnet and movable between a released position and an attracted position along a fixed path common to said driving members, movement of said armature from its attracted position into its released position moving any one of said driving members disposed in said path to count the corresponding impulse of said series, first means normally maintaining each of said driving members except the first out of said path, second means carried by each of said driving members except the last and cooperating with said first means and responsive to the counting movement of any one of said driving members except the last for preparing the positioning of the next succeeding one of said driving members into said path, and third means responsive to movement of said armature from its released position into its attracted position for positioning any prepared one of said driving members into said path, said third means also being responsive to the second movement of said armature from its released position into its attracted position for removing the first of said driving members from said path.

2. The counting device set forth in claim 1, wherein said third means is also responsive to the third and successive movements of said armature from its released position into its attracted position for removing the second and succeeding ones of said driving members from said path.

3. The counting device set forth in claim 2, wherein said third means is also responsive to movement of said armature from its released position into its attracted position following the counting movement of the last of said driving members for returning the first of said driving members into said path.

4. The counting device set forth in claim 1, wherein first means includes a plurality of multi-fingered rotatably mounted cocking elements, respectively operatively associated with the second and succeeding one of said driving members.

5. The counting device set forth in claim 4, wherein said second means carried by each of said driving members except the last includes a stud carried thereon and engageable with one of the fingers on the next succeeding one of said cocking elements, the counting movement of any one of said driving members except the last causing the one of said studs carried thereon to engage the one finger on the next succeeding one of said cocking elements rotating it to prepare the associated succeeding one of said driving members to be positioned in said path.

6. The counting device set forth in claim 1, and further comprising a plurality of ranks of movably mounted contactors respectively operatively associated with said driving members, said contactors being also arranged in a plurality of files, and a plurality of bar contacts respectively operatively associated with said files of said contactors.

7. In a counting device including a magnet for receiving a series of magnetizing impulses, a plurality of movably mounted driving members respectively corresponding to the impulses of said series, an armature operatively associated with said magnet and movable between a released position and an attracted position along a fixed path common to said driving members, movement of said armature from its attracted position into its released position moving any one of said driving members disposed in said path to

count the corresponding impulse of said series, first means normally maintaining each of said driving members except the first out of said path, second means carried by each of said driving members except the last and cooperating with said first means and responsive to the counting movement of any one of said driving members except the last for preparing the positioning of the next succeeding one of said driving members into said path, and third means including a rotatably mounted shaft carrying a pin and a bail and responsive to movement of said armature from its released position into its attracted position for positioning the next succeeding prepared one of said driving members into said path, said pin being disposed on one side of said shaft and portioned under the first of said driving members and said bail being disposed on the other side of said shaft and positioned under the second and succeeding ones of said driving members, said shaft having one position wherein said pin disengages the first of said driving members accommodating movement thereof into said path and wherein said bail engages the second and succeeding ones of said driving members moving them out of said path, said shaft having another position wherein said pin engages the first of said driving members moving it out of said path and wherein said bail disengages the second and succeeding ones of said driving members accommodating movement of any one thereof into said path.

8. In a counting device including an operating magnet for receiving magnetizing impulses thereto, a first series of impulses received by said magnet, other series of impulses subsequently received by said magnet, a first driving member and a plurality of additional driving members corresponding respectively to successive impulses in said series of impulses, an armature common to all of said driving members movable by said magnet and having a definite operating path for moving said driving members, means normally maintaining all of said driving members except the first out of said operating path, other means for positioning said first driving member within said operating path whereby only said first driving member is moved to count the first impulse in said first series, engaging means on each of said driving members except the last cooperating with said first mentioned means and said armature for successively positioning further driving members within said operating path, in which position they are successively moved to count their corresponding impulses in said first series, and after the driving member corresponding to the last impulse in said first series has been moved to count said impulse, the next succeeding driving member and further driving members will be positioned and moved to count their corresponding impulses in the next series by said first mentioned means, said engaging means and said armature; and in case the sum of said series of impulses exceed the total number of driving members after the last of said driving members has been moved to count the next successive impulse of said series, then said other means again positioning said first driving member within said operating path to count the next successive impulse of said series, the cycle now continuing in endless chain fashion counting the remaining impulses in said next series as well as any subsequent series of impulses received by said magnet.

9. In a counting device, a frame including a

base, a heelpiece and two parallel ears all rigidly connected together, a sub-base attached to and extending behind said base, there rising in a vertical wall flush against the rear of said heelpiece a plurality of ranks and files of contactors movably mounted to said vertical wall, a second pair of ears of an electrically insulating material affixed to said other ears extending there behind and above, a plurality of bar contacts mounted between said second pair of ears and ones of said bar contacts positioned rearwardly adjacent each file of said contactors, a plurality of driving members slidably mounted between said ears, each of said driving members insulatingly connected near one end to a rank of said contactors, rotatably mounted cocking elements individual to and below each of said driving members except the first, a bail and a pin rotatably mounted on opposite sides of a shaft, said shaft mounted between said ears, said bail beneath all of said driving members except the first and said pin beneath only said first driving member; a magnet mounted on said heelpiece beneath said driving members, cocking elements and bail and pin, for receiving a series of impulses thereto; an armature operable by said magnet responsive to an impulse received therein, a retractile spring for moving said armature in a definite retractile path upon termination of any of said impulses, all of said driving members except the first normally out of said armature's retractile path and so held by said individual cocking elements, said armature moving said first driving member responsive to the termination of the first of said series of impulses causing said attached rank of contactors to engage said rearwardly adjacent bar contacts, an engaging stud rigidly connected forwardly and to the right of each of said driving members, said stud on said first driving member engaging the cocking element beneath the next adjacent driving member to the right causing it to be rotated thereby removing its support and preparing said next adjacent driving member to be positioned within said armature path, restoring springs on each of said driving members, said restoring spring on said first driving member causing said first driv-

ing member to restore responsive to said second impulse of said series operating said magnet and armature, and said next adjacent driving member then dropping into said armature's retractile path causing said bail to lower thereunder raising said oppositely disposed-pin which raises said first driving member out of said path, each succeeding driving member being similarly positioned into said path to count its corresponding impulse, and spring means on each of said cocking elements for moving its individually associated driving member up out of said armature retractile path after it has been moved to count its corresponding impulse and has been restored, this sequence continuing until the last driving member has been moved and has counted its corresponding impulse, restored and has been returned to normal out of said armature's retractile path by its individual cocking element and spring means thereon, whereupon said bail is raised by the weight of said first driving member on said pin which is lowered again positioning said first driving member within said armature's path, this cycle being repeated in continuous chain fashion responsive to reception by said magnet of subsequent series of impulses.

10. In a counting device as claimed in claim 9, interrupter springs mounted onto said base and an arm on said armature for engaging and opening said springs each time an impulse has been received by said magnet, said springs tensioned to close when said armature is retracted by said retractile spring responsive to the termination of any of said impulses.
